UNITED STATES PATENT OFFICE.

CHARLES DE LUKÁCSEVICS AND JULIUS J. WITTAL, OF NEW YORK, N. Y., ASSIGNEES,
BY MESNE ASSIGNMENTS, TO EDMUND LOFFLER, OF NEW YORK, N. Y.

CARBURETER.

1,248,277.

Specification of Letters Patent. Patented Nov. 27, 1917.

Application filed March 23, 1916. Serial No. 86,058.

To all whom it may concern:

Be it known that CHARLES DE LUKÁCSEVICS and JULIUS J. WITTAL, a citizen of the United States and a subject of the King of Hungary, respectively, residing at New York, in the county and State of New York, have invented certain new and useful Improvements in Carbureters for Internal-Combustion Engines, of which the following is a specification.

This invention relates to carbureters for internal combustion engines and has as its principal object to provide a device of this character the essential parts of which are made of a non-conducting non-combustible and non-corrosive material, such as bakelite, condensite, or the like, adapted to be electrically heated by filaments embedded therein. A further object is to provide some novel features of construction of oil ducts and closing means therefor, whereby the gas supply may be regulated in a simple, effective and convenient way. A still further object is to provide, in such a device, a new construction of the air-admittance regulating means. Other objects of the invention will hereinafter appear as the description of the device proceeds.

Reference will now be had to the accompanying drawings, in which:

Figure 1 is a vertical cross sectional view of a carbureter constructed according to the present invention; Fig. 2 is a similar view of a modified form of embodiment of the invention, fragmentarily shown; Fig. 3 is a horizontal sectional view taken on the line 3--3 of Fig. 2, looking in the direction indicated by arrows; Fig. 4 is a partly sectional, partly elevational fragmentary view of a part of the device, removed; Fig. 5 is a view similar to that shown in Fig. 2, with further modifications; Fig. 6 is a horizontal cross-sectional view taken on the line 6--6 of Fig. 5 and Fig. 7 is an elevational detail view of a part of the device shown in Fig. 5.

Similar reference characters refer to similar parts throughout the several views.

Referring to the drawings by numerals, and omitting a detailed description of the parts which are old, 15 is the carbureter body pressed out of a non-conducting, non-combustible and non-corrosive material such as bakelite, condensite, or the like, in certain parts of which filaments 16 are embedded

and provided with binding posts such as 17 for connection with an electric circuit, adapted to heat the filaments. The heat thus produced in the interior of the walls of the carbureter body will prevent the condensation thereon of any moisture entering with the air and also facilitate the volatilization of the oil.

Within the body 15 and properly secured thereto is provided a cylinder 18 reduced at the outer periphery of its bottom part as at 19 giving the oil surrounding it access to a plurality of vertical ducts 20 provided in the walls of the cylinder 18 and communicating with the space inclosed thereby through spouts 21 obliquely bored through the cylinder walls and plugged from the outside thereof, as at 22. The spouts 21 open into the space inclosed by the cylinder 18, which serves as the carbureting chamber, at different levels, but several of them being at each level, evenly distributed on the circle of the inner circumference of the cylinder 18, at the respective level. The level of the oil surrounding the cylinder 18, indicated by dots and dashes in Fig. 1, is continuously kept below that of the lowermost spouts 21 by the well-known arrangement of a float 23 in connection with an admission valve 24. The oil therefore enters the carbureting chamber only through suction of the motor, when the engine feed valve, located between the spouts 21 and the engine suction tube 25 is opened by the operator, in the usual manner.

An annular sliding valve 26 is mounted in the cylinder 18 so as to cover all the spouts 21 except the uppermost ones, which it covers partly, in the closed position of the valve 25, as shown in Fig. 1. A rod 27 pivotally mounted in a recess formed in the bottom of the valve 25, as at 28, and pivoted to a pin 29 rigidly mounted in the sliding valve 26, is adapted to push the latter downward in the cylinder 18 in proportion to the extent of opening the valve 25, i. e., the more the valve 25 is opened, the more of the spouts 21 will be uncovered by the valve 26 and, consequently, the more fuel will be supplied to the engine. The symmetrical distribution of the several spouts at the same level, over the circumference of the circle formed thereby, will assure a uniform supply of oil from all sides, resulting in a thorough mixture with the air contained in the carbureting

chamber. The oil will also be thoroughly and uniformly volatilized by the comparatively small gage of the spouts 21.

Integrally formed with the cylinder 18, 5 at the lower end thereof, are inwardly projecting radial spokes 30 supporting an internally threaded hub 31 into which is secured a screw bolt 32 threaded at its upper and lower ends and plain therebetween. A 10 nut 33 is provided on the lower threaded end of the bolt 32, by means of which the air flue 34 and a cage 35 are tightened to the carbureter body 15, as may clearly be seen in Fig. 1. The cage 35 is provided with 15 holes 36 and is surrounded by a cup-shaped shutter 37 ending in a tubular downward projection 38 which rests slidably on the top surface of the nut 33. The shutter is provided with holes adapted to register with 20 those of the cage 35, and to shut them partly or entirely by turning the shutter around, for which purpose it is provided with a handle 39. The admittance of air from the air flue into the cage may thus be obviously 25 regulated by the shutter 37.

In the cage 35 is formed a valve seat 40 into which fits a tapering, hollow valve 41 slidably mounted on the bolt 32 by means of a sleeve 42. It is held on its seat by a 30 coil spring 43, the upper end of which is confined by a shouldered nut 44 held firmly in position on the upper threaded end of the bolt 32 by a pin 45, whereas the lower end of the spring 43 rests on the bottom of the 35 valve 41. The tension of the spring 43 may be regulated by turning the bolt 32 which latter is locked in the desired position by the nut 33. This nut thus serves for two distinctly different purposes.

40 It will be understood that when the valve 25 is open and the engine connected to the carbureter is started, a suction by the former takes place and creates a vacuum in the latter, whereby the valve 41 will be raised 45 from its seat in opposition to the spring 43, thus admitting air from the lower part of the cage 35. The oil supply will automatically be regulated by the extent of opening the valve 25 connected to and acting upon 50 the slide valve 26 which thus opens up a corresponding number of spouts 21, and the air supply, the required proportion of which may be determined by the tension of the spring 43 and by the shutter 37, will be 55 regulated by these two factors, so that the desired quantity and proportion of oil and air may be fed to the engine, thoroughly mixed and volatilized by the symmetrically distributed and comparatively small gage 60 spouts 21, as also on account of the heating of the interior of the carbureter.

In the modified form of embodiment of the invention shown in Fig. 2, in which the air flue has been omitted, the connection 65 between the valves 25 and 26 has been elimi-

nated and the latter is connected, instead, to the valve 41 by means of vertical rods 46, as shown. In this form of embodiment, the increase of the oil supply is attained by an upward movement of the slide valve 26, as 70 against the downward movement thereof in the first described form of embodiment and, consequently, the lowermost spouts 21 are partly uncovered by the valve 26 in the closed position shown in Fig. 2.

The number of spouts 21 uncovered is, 75 also in this form, automatically, although indirectly governed by the extent of opening of the valve 25, by means of the amount of vacuum resulting in the carbureting 80 chamber of the carbureter, which controls the extent of rise of the valve 41 from its seat and thereby the extent of movement of the sliding valve 26.

The bolt 32 is, in this form, substituted 85 by a tube 47, screwed into the hub 31 and provided, at its lower end, with an outwardly projecting flange 47^a which supports and secures in place the cage 35. On it rests, too, the shutter 37.

The upper end of the tube 47 is provided 90 with four equidistant longitudinal slots serving as guides for an equal number of lugs 48 formed near the upper end of a rod 49 slidably mounted in the tube 47 and protruding out of the lower end thereof. A plug 50 is inserted in the upper end of the tube 47 as a reinforcement to counter-balance the weakening effect of the slots before-mentioned.

The spring 43 is, in this form, coiled 95 around the tube 47 and confined by the lugs 48.

On the protruding lower end of the plunger 48 is coiled another spring 51, weaker, 100 but normally under higher tension than the spring 43 which latter, in the closed position of the valve 41, shown in Figs. 1 and 2, is practically fully expanded. The spring 51 is held under tension between the bottom 105 surface of the flange 47^a and a cup 52 on the lower threaded end of the rod 48 and locked in the desired position by a nut 53. The suction of the engine will thus first act on the weaker spring 51, until the limit is 110 reached by the contact of the upper edge of the cup 52 with the bottom surface of the flange 47^a and, with a constant moderate suction, this position of the parts described 115 will remain fairly steady, thus practically eliminating the vibration of the air admission valve usually obtaining in similar devices. When the suction is considerably increased, the spring 43 will come into play, 120 shutting the valve down to normal as soon as the stronger suction ceases, thus affording a perfect automatic control of the air admission by the manipulation of the valve 25 and the speed of the engine.

As will be seen in Fig. 2, the cylinder 18 125

is, in this form, substituted by a triple cylinder consisting of a cylindrical downward projection 54 of the body 15 itself, a metallic reinforcing core 55 inside of the projection 54, integral with the spokes 30, and a lining 56 of the same material as the body 15, inside of the reinforcing core 55, all in close contact with and conveniently secured to each other. In this modification the ducts 19, instead of being bored in the cylinder, are molded into the downward projection 54, as at 57. The spouts 21 are formed by oblique bores through the walls of the core 55 and the lining 56, at corresponding points, thus doing away with the plugging.

The second modification of our device, shown in Figs. 5-7, in which the air flue has been omitted, embodies the same general features of construction and arrangement which are employed in the form shown in Fig. 2. However, in this modification the shutter 37 is arranged inside of the cage 35, with such minor constructional changes as are involved by this arrangement and clearly shown in Figs. 5 and 7. One of these changes is a slot 58 made in one side of a hole 36 of the cage 35 (Fig. 7) to admit therein the handle 39 of the shutter 37 when the latter entirely uncovers the holes 36. The shutter 37 has, in its center, an upwardly projecting sleeve 59 provided, at one portion of its top edge, with a cam 60, a similar cam 61 being formed on the bottom surface of the valve 41. These cams are arranged to coöperate, when the shutter is in fully closed position, as on starting, in holding the valve 41 in a slightly elevated position and, through the intermediary of said valve, in holding the sliding valve 26 in a slightly elevated position whereby the lowermost spouts 21 will be uncovered and open to the carbureting chamber.

To overcome the torsional strain on the valve-rods 46 when the cams thus act against each other, they are guided through holes 62 provided in the spokes 30. As may be seen in Fig. 5, the valve 41 is in this form also made of the same material as the body 15.

It must be understood that each of the various modifications of certain features of our invention shown and described may be interchanged and combined in any form of embodiment of our invention and any further alterations and modifications may be resorted to without departing from the principles as set forth in the claims hereunto annexed.

We claim:

1. In a carbureter for internal combustion engines, a chamber for mixing the oil with air, ducts in the walls of said chamber having their spouts opening thereinto at different levels, an engine feed valve located between said spouts and the engine suction

tube, and means controlled by the extent of opening of said feed valve for opening up or closing down a larger or smaller number of said spouts.

2. In a carbureter for internal combustion engines, a chamber for mixing the oil with air, ducts in the walls of said chamber having their spouts opening thereinto at different levels, an engine feed valve located between said spouts and the engine suction tube, a sliding valve normally covering said spouts and means connecting said sliding valve to the engine feed valve, adapted to remove said sliding valve from a larger or smaller number of said spouts in proportion to the extent of opening said engine feed valve.

3. In a carbureter for internal combustion engines, in combination a cage, a spring-controlled air admittance valve having its seat in said cage, an air flue enveloping said cage, means for regulating the tension of said valve-controlling spring, and means for securing said cage and said air flue to the carbureter body, said securing means being also adapted to hold said spring-regulating means in the desired position.

4. In a carbureter for internal combustion engines, ducts provided in the walls of the carbureting chamber for feeding oil thereto, said ducts opening in said chamber at different levels, an air-admittance valve controlled by the vacuum created in said carbureting chamber and by counter-acting resilient means and means controlled by the extent of opening of the engine feed valve of the carbureter for closing and opening a larger or smaller number of said oil ducts.

5. In a carbureter for internal combustion engines, ducts made in the walls of the carbureting chamber for feeding oil thereto, said ducts opening into said chamber at different levels, an air admittance valve controlled by the vacuum created in said carbureting chamber and by counteracting resilient means, and a sliding valve adapted to close and open a larger or smaller number of said ducts according to the extent of opening of the engine feed valve of the carbureter.

6. In a carbureter for internal combustion engines, in combination a cage provided with a shutter for regulating the admission of air into said cage, an air admission valve controlled by the vacuum created in the carbureter and by counteracting resilient means, seated in said cage, and means provided on said shutter and on said air admission valve for forcibly raising the latter from its seat when the former is entirely closed.

7. In a carbureter for internal combustion engines, in combination a cage provided with a shutter for regulating the admission of air into said cage, an air admision valve

seated in said cage, controlled by the vacuum created in the carbureter and by counter-
acting resilient means, and cams provided
on said shutter and said air admission valve
5 for forcibly raising the latter from its seat
when the former is entirely closed.

8. In a carbureter for internal combustion engines, a carbureting chamber open at its lower end for the admission of air, ducts
10 formed in the wall of said chamber and having discharge spouts opening into said chamber at different levels, an engine feed valve located between said spouts and the

engine suction tube, and an annular valve
closely fitting said chamber wall and slid-
able lengthwise thereof, said annular valve
being controlled by the extent of opening
of said feed valve for exposing or occluding
a larger or smaller number of said spouts.

In testimony whereof, we affix our signatures
in the presence of two witnesses.

CHARLES DE LUKACSEVICS.

JULIUS J. WITTAI.
